UNITED STATES PATENT OFFICE.

LOUIS SEVERUS, OF CHICAGO, ILLINOIS, ASSIGNOR TO ART LAMP MANUFACTURING COMPANY, OF CHICAGO, ILLINOIS.

DESIGN FOR A LAMP BASE.

Application filed January 3, 1925. Serial No. 11,881. Term of patent 3½ years.

To all whom it may concern:

Be it known that I, Louis Severus, a citizen of the United States, residing at Chicago, in the county of Cook and State of Illinois, have invented a new, original, and ornamental Design for a Lamp Base, of which the following is a specification, reference being had to the accompanying drawings, forming part thereof.

Fig. 1 is a fragmentary top plan of the new and original lamp base, the balance of the ornamentation within the dotted outline being a repetition of the fragment shown.

Fig. 2 is a side elevation of the new and original lamp base.

I claim:

The ornamental design for a lamp base as shown.

LOUIS SEVERUS.
